(57) **CLAIM**

The ornamental design for a key for vehicle as shown and described.

DESCRIPTION

FIG. 1 is a perspective view of a key for vehicle showing my new design;

FIG. 2 is a front view thereof;

FIG. 3 is a rear view thereof;

FIG. 4 is a top plan view thereof;

FIG. 5 is a left side view thereof, the right side being a mirror image thereof; and,

FIG. 6 is a bottom view thereof.

The broken lines illustrate portions of the key for vehicle that form no part of the claimed design.
